WET-TREATING FIBROUS MATTERS

Sten Eskil Einarsson Ahlfors, Hedemora, Sweden

Application July 8, 1946, Serial No. 682,021
In Sweden July 11, 1945

3 Claims. (Cl. 92—33)

1

This invention relates to apparatus for wet-treating fibrous substances, particularly for straining, classifying, dewatering, washing and similar treatments of liquid suspensions of fibres, such as paper pulp.

One of its objects is to provide an improved apparatus for performing a vibratory method of wet-treating fibrous substances resulting in maximum output per unit area of an apertured member forming a basic element of the apparatus.

Another object is to provide simple and effective means for varying the pulsating pressure to which the suspension undergoing vibratory treatment is subjected, to suit different characteristics of the fibrous suspension, as well as varying conditions of operation.

Still another object is to utilize effectively the phenomena of resonance and beating in wet-treating fibrous substances.

The invention comprises the novel means hereinafter fully described and particularly pointed out in the claims hereunto appended.

The invention is illustrated by way of example on the annexed drawing in which:

Fig. 1 shows a side elevation of a strainer according to one embodiment of the invention.

Fig. 2 shows a central longitudinal section substantially along line II—II in Fig. 3.

Figs. 3 and 4 show transverse sections substantially along lines III—III and IV—IV respectively in Fig. 1.

Fig. 5 shows a side elevation of a strainer embodying a second form of the invention, a gearing associated with the vibratory apparatus of the strainer being shown somewhat diagrammatically.

Fig. 6 shows an end elevation of said strainer as viewed from the right-hand end of Fig. 5.

Fig. 7 shows a longitudinal section substantially along line VII—VII in Fig. 6.

Fig. 8 shows a transverse section substantially along line VIII—VIII in Fig. 7.

Fig. 9 is a side elevational view of a modified embodiment.

Fig. 10 is an end view partly in section of said modified embodiment.

Fig. 11 is a longitudinal central sectional view of said modified embodiment.

Referring to Figs. 1—4 the embodiment illustrated therein comprises generally two vats 1 and 2 the latter of which has an apertured curved strainer element 3 rigidly secured thereto and constituting the bottom thereof. Clamped to the lower marginal portion of vat 2 and to the upper marginal portion of vat 1 is a flexible dia-

2

phragm 4 permitting limited relative movement of vats 1 and 2.

Vat 1 is formed with leg members 5 apertured at their bottom ends as indicated at 6 in Fig. 1 forming bridge members 7 resting against resilient or elastic members 8, such as springs or rubber pads united to metal plates at the top and bottom face of each pad, and carried by bed plates 9 supported by a foundation diagrammatically indicated at 10. Resting on the top face of each bridge member 7 is a second resilient or elastic member 11 of similar construction in contact with a bridge member 12 adjustably mounted on bolts 13 rising from bed plates 9. 15 Carried by the upper ends of bolts 13 are nuts 14 by means of which the pressure exerted by bridge members 12 against members 11 and thus against members 8 through the agency of bridge members 7 may be varied at will to adjust the resiliency or elasticity of means 8, 11 and thus the damping of vat 1 when vibrated as set forth in the following.

Strainer vat 2 is resiliently supported by vat 1 in a manner now to be described.

Resting on brackets 15 laterally projecting from vat 1 are coil springs 16 compressed by means of washers 17 slidably mounted on rods 18 depending from tubular members 33 passing longitudinally through vat 2. Threaded on rods 18 are nuts 19 by means of which the compression of springs 16 may be varied at will. Similar means comprising coil springs 16, washers 17 and nuts 19 are mounted below brackets 15 and by this means and the equivalent means above brackets 15 the movement of vat 2 when vibrated as set forth in the following may be controlled to some extent. As clearly shown in Fig. 3 rods 18 have sufficient lateral play in brackets 15 to permit any desired lateral movement of vat 2 when vibrated.

40 Suspended by rods 18 is a vibratory apparatus comprising two double bearings 20 clamped at opposite sides between nuts 34 threaded on rods 18 as may be clearly seen from Fig. 1. Journalled in said bearings are two rotary shafts 21 each carrying two unbalanced or eccentrically arranged masses 22 serving to vibrate strainer vat 2 when shafts 21 are rotated. In the embodiment shown the rotation of shafts 21 is effected from an electric motor 23 by means of a shaft 24 connected to motor 23 and one of shafts 21 by means of flexible couplings 25, shafts 21 being interconnected by a suitable spur gearing (not shown). By this means shafts 21 are rotated in mutually opposite directions whereby

the horizontal forces from the rotating unbalanced masses 22 may be caused to neutralize each other to secure a substantially rectilinear vertical vibratory movement. Alternatively the form and inclination of the elliptical orbit of vibration may be varied at will by mounting unbalanced masses 22 of different sizes on each of said shafts 21 to suit any requirements met in practice. The vibratory movement from the vibratory apparatus is preferably applied to strainer vat 2 including strainer element 3 symmetrically to its center of gravity and pressure when loaded by the suspension to be treated and moving therein.

The embodiment of my improved strainer above described operates as follows.

The fibrous suspension to be treated is supplied to the strainer vat 2 at any suitable point, such as at A in Figs. 1 and 2 from any suitable supply diagrammatically illustrated as a launder 26 with adjustable outlet 27 permitting a control of the incoming suspension so as to maintain a suitable level of liquid in strainer vat 2 as indicated at L in Fig. 2. The suspension thus introduced tends to pass through the apertured strainer element 3 which together with the body of strainer vat 2 is caused to vibrate rapidly by means of the vibratory apparatus above described. This vibration is effected directly mechanically from the vibratory apparatus while the lower vat 1 is indirectly vibrated firstly hydraulically from strainer element 3 through the agency of the liquid of the suspension undergoing treatment and secondly mechanically by adjustable forces applied from vat 2 over springs 16, the vibration of vat 1 being possible due to the mode of resiliently supporting and clamping vat 1 by means of elements 8, 11, 12, 13 and 14 as described in the foregoing. The vibration of vat 1 will take place at a considerably smaller amplitude than that of vat 2, due to the relatively loose coupling through the liquid 1, the inertia of vat 1 and the damping produced by elements 8 and 11. According to the foregoing such damping may be easily adjusted to control the difference of amplitude between vats 1 and 2 and thus the pulsating pressure produced in the liquid between said vats.

The liquid of suspension and accompanying solids passing through strainer element 3 is continuously discharged at B into a suitable receiver shown as a launder 28 provided with a tubular stud 29 connected to a tubular stud 30 at the right-hand bottom end of vat 1 by means of a flexible tubular member 31 permitting vat 2 to vibrate.

The liquid of suspension and accompanying solids rejected by strainer element 3 is continuously discharged from vat 2 at C and received by launder 32.

The embodiment shown in Figs. 5-8 differs generally from that above described in that only one vat 2 is used the bottom of which is vibrated directly from a vibratory apparatus similar to that described with reference to the first embodiment whereas strainer element 3 is vibrated indirectly through the agency of the liquid of the suspension undergoing treatment. For the remainder the two embodiments are generally similar and it appears, therefore, sufficient to describe the detailed construction of the second embodiment merely in the respects in which it differs from the first embodiment, similar reference characters being used in all of the figures of the drawing to represent corresponding parts.

As indicated above, in the second embodiment the vibratory apparatus is associated with the bottom of vat 2 which to this end is connected to the body of said vat by means of a flexible diaphragm 4 clamped between upper and lower plates 39 and 40 respectively. Suspended from plate 40 by means of channel irons 41 is the vibratory apparatus the two double bearings 29 of which are bolted to channel irons 41 and to plate 40 as shown diagrammatically on the drawing.

Vat 2 is resiliently supported from bed members 42 by means of resilient or elastic, preferably replaceable members 8 clamped to vat 2 and to members 42 by threaded bolts 36.

Raising from bed members 42 are standards 18 clamped at their bottom ends to members 42 by nuts 43. Surrounding standards 18 are lower coil springs 16 resiliently supporting channel irons 44 secured to channel irons 41 and resting on said springs 16 by means of washers 45. Although not specifically shown standards 18 have lateral play in elements 44-46 just as rods 18 in the first embodiment have lateral play in brackets 15. Similarly upper springs 16 surround standards 18 above channel irons 44 and rest against washers 46 in contact with the top face of channel irons 44. The tension of coil springs 16 may be varied simply by adjusting nuts 19 to suit any requirements met in practise as regards the vibrations imparted to plates 39, 40 by the vibratory apparatus.

As to the latter it may here be mentioned that the gearing interconnecting shafts 21 and not shown in the first embodiment has been illustrated diagrammatically at 37 in Figs. 5-7.

As may be seen from Figs. 5 and 6 the upper ends of standards 18 are clamped together by channel irons 47 secured between nuts 48 at the top of standards 18. By this means nondesired, lateral movements of standards 18 and the elements associated therewith are prevented. Besides, channel irons 47 may be utilized to control the damping of vat 2 by adjusting nuts 48 whereby elastic or resilient members, such as iron clad rubber pads 11 may be pressed by any desired force against brackets 50 laterally projecting from vat 2 as clearly shown in Fig. 6.

As to the operation of the second embodiment it appears sufficient to mention that the fibrous suspension to be treated is supplied at A in Fig. 7 and tends to move upwards through apertured strainer element 3 which is caused to vibrate rapidly through the agency of the liquid of the suspension from elements 4, 39, 40 vibrated directly from the vibratory apparatus. The matter passing through strainer element 3 is continuously discharged at the top face thereof as indicated diagrammatically at B whereas the matter rejected by strainer element 3 is continuously discharged at the bottom face of element 3 as indicated at C through bell-shaped member 51 and central tube 52 mounted therein as may be clearly seen from the arrows in Figs. 7 and 8. Further description of such discharge means appears superfluous as such means forms no part of my invention.

In the embodiment represented in Figs. 9, 10, and 11, a single vat 63 is provided which is divided by a substantially horizontal strainer element 61 secured to the vat walls. A flexible diaphragm 62 is clamped at its edges between upper and lower plates 64 and 65 respectively. Suspended from plate 65 by securing arms 66 is a vibratory apparatus having double bearings 68.

The vibratory apparatus includes a pair of drive

shafts 69 connected so as to be driven in opposite directions, and on each said shaft is mounted a pair of eccentrically arranged masses 70, 70. Rapid turning of the drive shafts 69 and masses 70 imparts to diaphragm a rapid vibration, which in turn is imparted to the substance contained in vat 60. Gearing interconnecting the drive shafts is diagrammatically shown at 67. Vat 60 is mounted on resilient or elastic members 71 which in turn rest on fixed stationary bed plates 72, and the vat is prevented from becoming displaced by bolts 74, which extend through portions 75 of the vat, the elastic members 71, and the stationary plates 72, mounted on foundation 73.

On the upper edges of the vat 60 are mounted further double bearing members 68' which rotatably mount a pair of further drive shafts 69' which are geared together as diagrammatically represented at 67' to rotate in opposite directions. These drive shafts are each provided with a pair of eccentric masses 70' which impart rapid vibration motion to the vat 60 when the drive shafts 69' are rotated.

The vat 60 and lower plate 65 are resiliently interconnected by means of a set of coil springs 76 which are clamped between securing arms 66, mounted on lower plate 65, and washers 77 mounted on threaded rods 79, which are connected at their upper ends to brackets 80 on the sides of vat 60. The tension or compression in springs 76 can be adjusted by turning nuts 81 on the lower ends of rods 79.

Electric motors 84 and 85 are shown as the drive means for the shafts 69, 69', respectively. To allow for the vibrations of the vibratory members on which shafts 69, 69' are mounted, flexible couplings 86, 86' are interposed in the connections between the drive motors and the respective shafts.

In operations the vat 60 and diaphragm 62 are vibrated at mutually different rates. The fibrous suspension enters the vat at the point indicated by arrow A; liquid of suspension and solids passing the strainer leave by discharge B and the liquids of suspension and solids rejected by the discharge C.

Although in the embodiments above described the two elements are assumed to be vibrated by means of rotary shafts supporting unbalanced masses it is, of course, within the scope of my invention to effect the vibration by any other mechanical means, for instance, by eccentrics and pitmans positively vibrating either element, or by hydraulic, pneumatic, electric or magnetic means.

It is also within the scope of my invention to allow either element to vibrate at more or less pronounced resonance to amplify the vibrations as desired.

In the preferred embodiments of my invention the two elements are vibrated with mutually different amplitudes whereby the pulsating pressure acting upon the suspension between said elements may be increased or decreased simply by increasing or decreasing the difference in amplitude between said two elements. By vibrating both elements directly at equal frequency but in opposite phase the intensity of the pressure and suction impulses produced in the suspension between the two elements in response to the vibration thereof may be still more increased. By vibrating the two elements at mutually different frequencies recurrent pulsations of increased amplitude may be obtained according to the well known phenomenon of beating, such as for automatically

cleaning the apertured element from fibrous substances tending to clog therein.

From the foregoing it may be seen that I have invented a new method of wet-treating fibrous substances resulting in many advantages.

Before all, the output per unit area of the vibrating apertured element is materially increased by simultaneously differently vibrating the opposite non-perforated element in that both elements then act positively on the suspension undergoing treatment.

Another advantage of my improved method resides therein that suspensions of relatively high fibrous contents may be continuously treated due to the more intense acting upon of the suspension in differently vibrating both elements.

Still another advantage of my invention will be clear when considering the dewatering or pumping effect produced in vibrating a strainer member having apertures presenting unequal flow resistances in opposite directions, such as tapering apertures, such effect being dependent substantially on the amplitude of vibration of the strainer element. According to my invention this effect may be utilized to the best advantage in different treatments of the suspension. Thus, if dewatering to a large extent is desired this result may be secured according to my invention by vibrating the strainer element directly with sufficiently large amplitude and controlling the amplitude of vibration of the second element indirectly vibrated, to avoid excessive pulsating pressures in the suspension. On the other hand, if dewatering to a smaller extent is desired, then the strainer element may be vibrated indirectly with relatively small amplitude and the second element directly with sufficiently large amplitude to secure the required pulsating pressure in the suspension.

Although the invention in the foregoing has been specifically described in connection with straining of fibrous suspensions it may obviously be applied to other wet-treatments of such suspensions, such as to classifying, dewatering or washing. The modifications of the method and apparatus then necessary are obvious to anyone familiar with the art.

What I claim is:

1. An apparatus for wet-treating fibrous substances, particularly for straining, classifying, dewatering and washing liquid suspensions of fibres, comprising means for supplying the suspension to be treated to said apparatus, a strainer vat having a strainer element rigidly secured thereto, a second vat situated therebelow and connected to said first mentioned vat by a flexible diaphragm, a rigid foundation, resilient means for supporting said second mentioned vat from said foundation, resilient means for supporting said first mentioned vat from said second mentioned vat, vibratory means suspended from said first mentioned vat and adapted to vibrate said strainer element and the part of said second mentioned vat mutually differently, so as to cause said suspension to partially pass through said strainer element, and means for discharging the part of said suspension passing through said strainer element at one face thereof and the part rejected by said strainer element at the opposite face thereof.

2. An apparatus of the class specified comprising in combination, a foundation, a vat having a yieldingly mounted rigid bottom, elastic means for supporting said vat on said foundation, a screen dividing the vat into a lower chamber and

an upper chamber communicating with each other through the orifices of the screen, an inlet for a suspension of fibrous material leading to said lower chamber, an outlet for finer fibrous material leading from said upper chamber, an outlet for coarser material leading from the lower chamber, springs for resiliently supporting the bottom of the vat, and vibratory means connected to the bottom of the vat for effecting a positive vibration of the bottom and due to the resilient mounting of the vat a vibration of the bottom and the screen at a different amplitude than that of the vibration of the bottom so as to effect a pulsatory pressure in the suspension between the bottom and the screen.

15

3. In an apparatus as claimed in claim 2, the further feature that additional vibratory means are provided in connection with the vat for positively controlling the amplitude of the vibration of the screen with relation to that of the bottom. 20
